UNITED STATES PATENT OFFICE

2,324,401

CASE SEALING MACHINE

Wallace D. Kimball, Jackson Heights, N. Y., assignor to Standard-Knapp Corporation, Portland, Conn., a corporation of New York

Application May 1, 1941, Serial No. 391,307

39 Claims. (CL 93—6)

This invention relates to apparatus for sealing cartons, and particularly cartons made of heavy corrugated board or fiberboard such as are in general use as shipping cases for many kinds of products. The bottoms and tops of such cases are closed by inner and outer flap extensions from the end and side walls respectively. The invention relates to improvements in carton closing apparatus of the kind disclosed in Patent No. 1,815,571 of Wallace D. Kimball and Arthur E. Rideout, and Patent No. 2,095,258 of Wallace D. Kimball and Cornelius I. Braren, both assigned to the same assignee as the present application.

In both of these prior patents the filled shipping cases or cartons are received resting on their bottom flaps and with the bottom flaps closed but unsealed. The top flaps may or may not be folded to closed position, and in passing through the apparatus the cases have both their top and bottom flaps opened and swung outwardly to horizontal position, in which position adhesive is applied and thereafter the flaps are refolded to closed position and pressed into sealing contact with one another. The cartons as they leave such apparatus are ordinarily passed directly into a "compression unit" or sealing pressure-applying apparatus by which the flaps are held in contact with one another until the adhesive has set.

The apparatus of the former patent was arranged for the adjustment of the flap-unfolding devices, glue-applying mechanism and flap-refolding and closing devices, together with appurtenant guiding rails so as to employ the apparatus for sealing cartons of different width and height. The adjustments were made by a mechanic and it was necessary to take the machine out of operation while it was being readjusted to handle cases of a different size.

In the apparatus of the latter patent, various parts of the machine were arranged to facilitate the making of the necessary adjustments so that it was possible to change a machine over to handle a different size of case in a very short time.

The object of the present invention is to provide a machine of this sort which is completely automatic as to its adjustability for case height and width. In manufacturing establishments where a number of different products are made, the cases in which the products are packed for shipment often differ considerably in size, both in height and width. Instead of providing a separate carton-closing apparatus to handle each of the different sized cases, such manufacturers

may desire to have a single carton-closing apparatus which will take successive cases differing widely in size, and it is the object of the present invention to meet this need and provide a carton-closing apparatus which is self-adjustable both as to the height and the width of case, so that, within the range of sizes for which the machine is designed, a wide, high case may be sent through the machine followed by a narrow, low case, or vice versa, and the machine will automatically accommodate itself to each case presented to it.

To this end the machine is arranged to gauge or caliper both the height and the width of each case delivered to it and then automatically adjust the flap-manipulating, adhesive-applying and case-guiding devices according to the measured dimensions of the case.

It is a further object of the invention to provide apparatus for carrying out these operations which is capable of giving reliable operation and high output.

The invention will be understood from a consideration of the accompanying drawings which illustrate, by way of example, the embodiment of the invention in a top and bottom gluing apparatus, although it will be understood that the invention is equally applicable to a machine which glues and closes the top flaps only, and that if desired certain features of the invention, such, for example, as the height adjustment, may also be applied to sealing pressure apparatus and the like. In the accompanying drawings:

Figs. 1a and 1b are complementary views which, taken together, represent the complete machine in plan view;

Figs. 2a and 2b are complementary views which show the machine in central vertical section taken on lines 2a—2a of Fig. 1a and 2b—2b of Fig. 1b;

Fig. 3 is a vertical section on an enlarged scale taken on broken line 3—3 of Figs. 1a and 4 showing the details of the case-feeding and timing mechanism;

Fig. 4 is a plan view of the timing mechanism shown in Fig. 3 drawn to the same scale;

Fig. 5 is a vertical section taken on broken line 5—5 of Fig. 4;

Fig. 6 is a transverse vertical section taken on the line 6—6 of Figs. 1b and 2b illustrating a portion of the motor driving mechanism for both height and width adjustment;

Fig. 7 is a view of the rear side of the machine which is on the right when facing the entrance, or front end of the machine, as shown in Figs.

1a-1b, illustrating the mechanism for gauging the height of the case entering the machine and drawn to a slightly enlarged scale;

Fig. 8 is a horizontal section taken on the line 8-8 of Fig. 7 illustrating certain details of the height-gauging mechanism;

Figs. 9-12, inclusive, are views similar to Fig. 8 showing parts of this mechanism in different operating positions;

Fig. 13 is a perspective view illustrating a detail of a portion of the height-gauging mechanism;

Fig. 14 is a perspective view showing certain other details of both the height and width adjusting mechanism;

Fig. 15 is a horizontal section taken on the broken line 15-15 of Fig. 2b drawn to a somewhat enlarged scale and illustrating parts of the mechanism for width adjustment of the upper flap unfolders and glue rollers. It also shows the mounting and adjustment of the case guides and top flap refolders at the rear end of the machine;

Fig. 16 is a somewhat similar view of the width adjustment of the same parts for operating on the bottom flaps, taken on line 16-16 of Fig. 2b;

Fig. 17 is a perspective view showing the construction and operation of the automatic mechanism for gauging the width of the case entering the machine;

Fig. 18 is a fragmentary plan view of the guides for gauging the case width set for the maximum width for which the machine is intended, and the motor-adjusted guides at the central part of the machine set at the minimum width for which the machine is intended;

Fig. 19 is a view similar to Fig. 18 illustrating the gauging and adjustment of the machine for a case of intermediate width;

Fig. 20 is a vertical section taken on line 20-20 of Fig. 6 with certain parts omitted showing the two width adjustment switches and illustrating the top and bottom gluing mechanism;

Fig. 21 is a vertical section taken on broken line 21-21 of Fig. 2b showing the mechanism for width adjustment of the case guides at the rear end of the machine and of the bottom flap refolders, and in addition the adjustment for both width and height of the top flap refolders and inner top flap holding bar;

Fig. 22 is a somewhat diagrammatic view to illustrate certain parts of the height and width adjusting mechanism referred to in connection with Fig. 21;

Fig. 23 is a sectional view taken on line 23-23 of Fig. 22; and

Fig. 24 is a diagram of electrical connections.

Referring now to these drawings, and particularly Figs. 1a, 1b, 2a and 2b, the general arrangement of the machine is not unlike the disclosures in the two patents mentioned above, particularly the second patent. It is a long, narrow structure having two side frame members 1 and 2 extending substantially from one end to the other. These are suitably supported as indicated. An elongated support consisting of a series of roller tables 3, 4 and 5 and a flat smooth platen, or table, 6 is arranged centrally between these frame members 1 and 2 to support the cases as they progress through the apparatus. At the left hand end of the machine there is a cross shaft 7 and near the right hand end a similar cross shaft 8. On these shafts are the usual sprockets carrying the usual pair of feeding chains 9 and carried

in spaced relation by these chains are the case driving bars 10.

The cases are fed into the machine at the left hand end by means of a timing or feeding-in mechanism indicated generally by numeral 11 which feeds the cases one at a time onto a constantly driven short endless feed belt 12 well in advance of each driving bar 10 so as to permit the gauging or measurement of the height of the case before the driving bar catches up with it. Feed belt 12 carries the case forward against a vertically shiftable stop plate 13 at the forward end of roller table 3. The cases are momentarily stopped at this gauging station while the height gauging mechanism, indicated generally by numeral 14 (Fig. 2a) operates. By the time the gauging operation is completed, one of the feed bars 10 arrives behind the case and pushes it forward onto roller table 4 where the width-gauging mechanism, indicated generally by numeral 15 (see perspective view 17) operates and at the same time shifts the case on rollers 4 as may be necessary to center it with respect to the platen or table 6. The case advances from roller table 4 onto the roller table 5 whose rollers are pitched downward so as to permit the outer side flaps of the carton to open somewhat, after which the carton advances onto platen 6, the pointed forward end of which enters beneath the outer or side flaps and supports the carton and its contents on its inner or end flaps.

As the carton advances over platen 6 (Fig. 2b) both the bottom and top side flaps are opened outwardly to horizontal position and adhesive is applied by the gluing mechanism indicated generally by numeral 16, after which both the top and bottom flaps are refolded to closed position against the inner flaps and the carton is delivered from the left hand end of the machine into the sealing pressure applying apparatus. During the time that the carton is advancing from the height-gauging mechanism 14 and past the width-gauging mechanism 15, the automatic adjustment of the height of the gluing mechanism 16 including the top flap unfoldes to accommodate the approaching case, is accomplished, and as well, the automatic width-adjustment, that is, the moving further apart, or closer together, of the glue rollers and flap unfoldes.

The automatic adjustment of the top glue rollers and flap unfoldes for height, and the automatic adjustment of both the top and bottom glue rollers and top and bottom flap unfoldes for width, is accomplished by means of electric motors 17 and 18, respectively (Figs. 1b and 6) which are operated in one direction or the other, as required, under the control of switches actuated by the height and width adjusting mechanism.

The height adjustment of the top flap refolders, inner flap-holding shoe and outer flap-closing shoe is accomplished by means of cam mechanism operated in timed relation with the driving bars 10. The width adjustment of both the bottom and top flap refolders and carton guides at the delivery end of the machine is also by mechanism cam-operated in timed relation to the driving bars 10.

Now describing the machine in detail, the main driving motor 19 (Fig. 1b) is mounted on a sub-frame at the left hand end of the machine. Through a belt 20 this motor drives a reducing gear 21. The slow speed shaft of this gear is connected, by means of a chain 22 and sprocket 23 (loose on cross shaft 7) to drive this shaft

through a slip clutch 24. Thus are the main feed chains 9 and the driving bars 10 operatively connected with the main driving motor 19. The various cam shafts and other rotating parts of the apparatus are driven by sprocket and chain connections from cross shaft 7 or cross shaft 8, as will be later described.

The timing or feed-in mechanism 11 is illustrated in detail in Figs. 2a, 1a and 3, 4 and 5. A short endless belt 25 is carried by rollers 26 and 27, roller 27 being on a shaft which extends between two stationary side frame members 28, in turn supported on the main side frame members 1 and 2. The other belt roller 26 is on a shaft which is rotatably mounted at the left hand end of a pair of pivoted frame members 29 which are pivoted at 30 adjacent roller 27. These side frame members 29 are joined together into a rigid structure by a series of cross rods which carry table rollers 31 to support the upper side of belt 25, and they are joined together at their left-hand ends by an angle bar 32 which forms a scuff plate to carry cases resting on the timer belt 25 against a stationary stop roller 33 when the left-hand end of this framework is in its low position, as shown in Figs. 2a and 3.

The cases are received on timing belt 25, usually from a roller conveyor from the case-packing machine and are held back by the stop roller 33 until the proper time, when the left hand end of timer belt 25 is raised by lifting the side frames 29 by mechanism to be described so as to elevate the front of the foremost case over the stop roller and allow the timing belt to push it forward onto the feed belt 12. Side guides 34 are provided above timing belt 25 and are adjusted to the width of the widest case which the machine is to accommodate on any particular run.

Timing belt 25 is driven by means of a sprocket on the shaft of roller 26 which is connected by a chain 35 with a sprocket 36 on cross shaft 8. The ratio of these two sprockets is such as to give timing belt 25 a speed which is substantially higher than the rate of movement of main feed chains 9, so as to advance the foremost case quickly over the stop roller 33 and onto feed belt 12. Thereupon frames 29 are lowered again to catch the next case against the stop roller, thereby feeding the cases one at a time into the machine.

The mechanism for raising frames 29 and the left-hand end of timer belt 25 is shown particularly in Figs. 3, 4 and 5. A lifting arm 37 is pivoted at 38 to side frame member 2 and its opposite end, which carries a knife 39, is periodically raised and lowered by means of a roller 40 which coacts with a cam 41 on cross shaft 8. To lift frame 29 an arm 42 carrying a catch plate 43 having at its lower edge an inverted V-shaped groove to be engaged by knife 39 is provided. When catch plate 43 is vertically above knife 39 the catch plate and arm 42 will be lifted bodily by the upward movement of arm 37 and knife 39. Arm 42 is loosely mounted on the end of a rod 44 and the arm is biased toward knife 39 by a helical spring 45 surrounding rod 44. Rod 44 extends crosswise beneath frame members 29 and is fixed to the outer end of a pair of short arms 46 adjacent and below each frame member 29 (one of which is illustrated in Figs. 3 and 4), these arms being pinned to a cross shaft 47 which is pivoted to stationary frame members 28. In order to connect frame members 29 with rod 44 so that the lifting of rod 44 will lift timing belt 25, a pair of short link

members 48 adjacent each of frame members 29, one of which is shown in Figs. 3 and 4, are provided.

It is desired not to have the timing belt 25 raised unless there is a case on this belt ready to be admitted to the gluer, and, furthermore, since cam 41 is on cross shaft 8 of the feed chains 9, and since this shaft makes three revolutions between the passage of successive drive bars 10, it is necessary to provide a control mechanism to control the shifting of arm 42 to bring catch member 43 into or out of engagement with knife 39.

In order to accomplish this, catch member 43 is made wider than the width of knife 39 as shown in Fig. 4, and two control members, 49 and 50, one on each side of knife 39, are provided. Both of these control members normally hold catch member 43 and arm 42 in a position at the right of knife 39 as shown in the drawings. Control member 50 is an S-shaped arm pivoted at 51 on a bracket on the bottom of side frame 2 and has a roller 52 which is engaged by a cam 53 which is driven, by means of a chain 54 and suitable sprockets, from cross shaft 8 in such a way as to make one revolution for each three revolutions of shaft 8. Cam 53 is also timed with respect to the advance of driving bars 10 so as to cause the movement of control member 50 to the left, and hence the delivery of a case onto feed belt 12, shortly after the passage of the guide bars beyond the end of the shiftable stop 13. In this way the feeding of each case is properly timed with respect to the operation of the gluer.

If there is no case present on the timing belt 25, however, the catch member 43 is held out of engagement with the knife 39 by means of the second control member 49 which consists of an arm extending upwardly from a shaft 55 (see Figs. 3 and 4) which extends crosswise of the machine and at its center carries a finger 56 (Figs. 1a and 3) which is engaged and moved forward by the foremost case into a recess 57 in stop roller 33. This movement of finger 56 shifts arm 49 to the left in Figs. 3 and 4 against an adjustable stop 58 and against the pull of helical spring 59 by which arm 49 is normally biased to hold catch member 43 out of engagement with knife 39. The shifting of arm 49 against stop 58 permits the engagement of catch member 43 by knife 39, and hence the raising of the timing belt 25, when cam 53 has rotated so as to actuate control arm 50 to permit this engagement.

When a case is received from the timing mechanism 11 on the feed belt 12 and advanced over roller table 3 against stop plate 13, this stop plate is in its elevated position, as shown in Fig. 2a. Feed belt 12 is driven by a roller 60 secured on cross shaft 3. Stop plate 13 is supported on a bar 61 which is carried at its ends on a pair of arms 62 pivoted on a shaft 63 which is carried in the side members 1 and 2. Stop plate 13 is urged toward its upper position by a helical spring 64 surrounding shaft 63 towards its right hand end. The arm 62 on this side of the machine has an extension 65 on which is a roller 66 engaging a cam 67. This cam is fixed to a main cam shaft 68 extending crosswise of the machine and driven by a sprocket 69 and chain 70 from a sprocket 71 on the outer end of cross shaft 8. A take-up sprocket 72 is provided for chain 70. At the center of cam shaft 68 there is a small cam 73 which actuates a pivoted lever 74 to lift the front edge of the rear flap of each case onto the front pointed end of the platen 6 at the proper time.

Referring now to the bottom gluing mechanism, this includes a pair of gluing or adhesive-applying rollers 75 (Fig. 16) which are adjustable laterally with respect to one another, a pair of lower guides 76 and a pair of flap unfolders 77 for unfolding the lower side flaps, both of which are adjustable laterally simultaneously with the bottom glue rollers 75. When the carton reaches the position shown in dotted lines in Fig. 2b, the outer or side bottom flaps have previously dropped open and are about to be engaged by the flap unfolders 77 shown in the form of warped surfaces which fold the flaps outwardly to horizontal position and guide them into contact with the upper surface of glue rollers 75, as shown in detail in Fig. 20, so that a coating of adhesive is applied to the lower surfaces of the unfolded flaps. Glue rollers 75 are rotated continuously by means of a sprocket 78 on the shaft 79 which extends crosswise of the machine to carry glue rollers 75. A chain 80 drives sprocket 78 from a sprocket 81 on cross shaft 7. To permit rollers 75 to be moved laterally they are connected to their supporting shaft 79 by splines 82.

To facilitate the power adjustment of the several parts, each of the adhesive receptacles 83, the support for each of the guides 76 and the support for each of the unfolders 77 are formed into a unitary assembly indicated generally by numeral 84 at each side of the machine. These assemblies are supported in transversely slideable relation on parallel stationary bars 85. Each assembly 84 has suitable arms engaging the opposite side of each glue roller 75 for shifting it along shaft 79 as the assemblies are adjusted with respect to one another to bring them closer together or farther apart.

To accomplish such adjustment of assemblies 84, one assembly 84 has a pair of rack bars 86, one beneath each of the supporting cross bars 85, and, in a similar position, the other assembly has secured to it a pair of rack bars 87. These pairs of rack bars 86 and 87 are operatively connected together at their centers by means of two pinions 88 secured on opposite ends of a short longitudinal shaft 89 mounted for rotation on a stationary part of the machine frame. By this arrangement, movement of one rack bar 87 in a given direction causes the assembly 84 to which it is secured to move in the same direction and the opposite assembly 84 to move in the opposite direction, thereby bringing the two assemblies 84 either closer together or moving them farther apart. By means of this arrangement also, the same motion is imparted to one side of each assembly as to the other side, so that they slide on their supporting bars 85 without binding and the guides 76 are maintained in parallel relation.

To produce the adjusting movement, one of the rack bars 87 is extended and has a second set of rack teeth 90 which engage a pinion 91 secured to a square vertical shaft 92. On the upper end of this shaft is a gear 93 and meshing with it is a pinion 94 on the output shaft 65 of a reduction gear 95 to which width adjusting motor 18 is connected.

The above completes the description of the power-operated adjusting mechanism for the lower gluing mechanism. The upper or top flap gluing mechanism is of similar construction except that the transverse supporting bars 85a are arranged for vertical adjustment under the operation of height-adjusting motor 17. The cross bars 85a comprise the principal cross mem-

bers of a vertically adjustable carriage which is indicated generally by numeral 96. The end members of this carriage 96 into which bars 85a are anchored comprise two end frames 97 and 98 which are slideable vertically on posts 99 and 100 respectively. The description of the gluing mechanism will not be repeated in detail. It will be understood, however, that the upper adhesive receptacles 83a are modified in form in order that the glue rollers 75a may apply adhesive to the upper surfaces of the unfolded top flaps.

The adjustment of the two upper assemblies 84a toward or away from each other is produced in the same way as that of the two lower assemblies 84, that is to say, by means of an extension of rack bar 87a which has a set of rack teeth 90a that engage a pinion 101. This pinion, however, differs from pinion 91 in that it is vertically slideable on the square driving shaft 92 so that width motor 18 can be operated to effect the adjustment of both the upper and lower gluing mechanism assemblies 84 and 84a simultaneously, regardless of the height to which the carriage 96 may be adjusted by the operation of motor 17.

The driving connections between height adjusting motor 17 and vertically adjustable carriage 96 are illustrated in Figs. 6 and 2b. A belt 102 from the motor operates a reduction gear 103 and a sprocket 104 on the output shaft of the reduction gear drives a sprocket 105 by means of chain 106, sprocket 105 being on the outer end of a cross shaft 107 which is rotatably mounted in stationary frame members carried by the tops of vertical posts 99 and 100. A set of pinion teeth 108 cut in the surface of shaft 107, mesh with the teeth of a vertically movable rack bar 109 on one side of the machine, and a second set of pinion teeth 110 similarly engage a second rack bar 111 on the opposite side of the machine. These rack bars 109 and 111 slide in the frame members at the top of posts 100 and 99 respectively and are secured at their lower ends to the opposite ends of the vertically adjustable frame 96 carrying the upper glue roller, etc. (Fig. 6).

In order to drive the upper glue rollers 75a, a short shaft 112 (Fig. 16) is driven through gearing 113 from lower glue roller shaft 79, in order to change the direction of rotation. Short shaft 112 is operatively connected with upper glue roller shaft 79a by means of two sets of chains 114 and 115 and their coacting sprockets, as illustrated in Figs. 16 and 7. Further details are set forth in Patent No. 2,095,258, above referred to.

In addition to the flap-folding and glue-applying mechanism previously described, vertically adjustable carriage 96 carries a pivoted member 116 for initially opening the outer top flaps before they are engaged by the unfolders 77a. Also the bars 85a carry at the center a frame member to which is bolted a forwardly and upwardly projecting stationary arm 117 at the outer end of which a rotary folder 118 is supported. This folder is rotated in timed relation to the advance of the case by the driving bar 10 to push down the rear inner flap, as shown in Fig. 2b, beneath the member 116. Folder 118 is rotated by chain 119 (Figs. 1b and 2b) which is guided beneath idler sprockets shown in Fig. 2b and passes over a driving sprocket 120 on glue roller shaft 79a.

Returning now to case gauging mechanism 14

at the forward part of the machine as illustrated in Figs. 2a and 1a, it has been mentioned that a case fed into the machine from the timing mechanism 11 is stopped against the vertically shiftable stop plate 13. This stop plate is beneath the gauging mechanism 14, and while the case is momentarily stopped by plate 13, a detector or gauging bar 121, which is provided at its lower end with a freely swinging pivoted plate or shoe 122, is lowered until the shoe 122 touches the top edge of the front wall of the case. The shoe 122 enters between the two side flaps of the case (which, because of their natural stiffness, are open sufficiently to permit its entrance), and forces down the forward inner flap to horizontal position, shoe 122 swinging on its pivot to horizontal position at this instant.

The mechanism for raising and lowering gauging bar 121 is illustrated in Figs. 2a, 1a, 7 and 8. The gauging bar 121 is vertically slidable in a bracket 123 which is fixed to a horizontal bar 124 that extends between two stationary posts 125, one at each side of the machine. One side of gauging bar 121 has rack teeth 126 that engage pinion teeth formed near one end of a horizontal shaft 127 which is arranged for rotation in bracket 123 and in a second bracket 128 secured at the upper end of one of the posts 125. At its outer end shaft 127 is provided with a second set of pinion teeth 129 which are engaged by a set of rack teeth in an upwardly shiftable bar 130. This bar 130 is connected at its lower end to a long lever 131 which is pivoted at its left hand end at 132 to the side frame 2. Lever 131 carries a roller 133 which engages a large disc cam 134 which is fixed on cam shaft 63, previously referred to. Lever 131 and roller 133 are urged downwardly to maintain the roller in contact with cam 134 by means of a large helical spring 135 (Fig. 7). Since this cam shaft is constantly driven and makes one revolution for the passage of each driving bar 10, the gauging bar 121 is lowered periodically regardless of whether or not a case is present at the gauging station.

The stroke of gauging bar 121 carries the shoe 122 upward above the flaps of the largest case which the machine is designed to accommodate (Fig. 2a) and downward to the lowest dotted position which is below the height L of the lowest case that the machine is designed to take, provided there is no case in the machine. When there is a case at the gauging station, the downward movement of the gauging bar 121 is arrested when the shoe 122 comes into engagement with the case, the cam 134 leaving roller 133 temporarily or until, on its continued rotation, the cam re-engages this roller and lifts the gauging bar 121 back to its uppermost position. During this period while the cam is out of contact with the roller, leaving the gauging bar in contact with the case, the control mechanism is set.

In connection with Figs. 2a and 7-12, inclusive, it will be understood that the reference letters H and L and the dotted positions of the various parts corresponding thereto indicate the positions of the parts for the highest and lowest cases, respectively, for which the machine is designed, and the reference letters M₁ and M₂ indicate the positions of the parts corresponding to cases of two intermediate heights.

The lowering of gauging member 121 into contact with a case by the movement of lever 131 causes the shifting toward the left of a horizontal control setting bar 136 which is operatively con-

nected therewith by rack teeth engaging a third set of pinion teeth 137 formed in the surface of shaft 127. The movement of this bar corresponds exactly with the movement of gauging bar 121 except that it is a horizontal movement instead of a vertical one. Thus the head piece 138 on the right hand end of setting bar 136 is almost at the position shown in Fig. 8 when the gauging bar is in its uppermost position, and as the gauging bar moves downward the head piece 138 moves a corresponding distance to the left.

Located adjacent and parallel with setting bar 136 (Figs. 7-12) is a long horizontal control bar 139 which forms part of the control mechanism and which is slidably supported at its left hand end in bracket 128 and at its right hand end in one of the frame members mounted at the top of posts 100. Control bar 139 is urged to the right by means of a helical spring 140 bringing a collar 141 fixed on this bar into engagement with the frame member just referred to, and fixing the normal or reference point position of bar 139 to which it is always returned when released by the setting mechanism about to be described.

Secured to control bar 139 are two straight cam plates 142 and 143. Plate 142 is on the lower surface of the bar and plate 143 on the upper so that they are spaced vertically a slight distance apart. Their inner ends are preferably rounded or sloped as illustrated and are also spaced horizontally a slight distance apart, sufficient to accommodate rollers on the ends of the actuating levers of two electrical switches 144 and 145 (Fig. 13). The connections within these switches are shown in Fig. 24 from which it will be understood that when the actuating levers are in their outward positions which they are permitted to assume when the ends of these levers are between the ends of cam plates 142 and 143 (as shown in Fig. 24 and also in Figs. 8, 10 and 12), the switch contacts are opened so that no current can flow.

When, however, the lever of switch 144, for example, is pushed inwardly by engagement with the edge of plate 142, as shown in Fig. 11, for example, the contacts of switch 144 are closed. Similarly, when the operating lever of switch 145 is pushed inwardly by engagement with cam plate 143 as shown, for example, in Fig. 9, the contacts of switch 145 are closed. Furthermore, only one of these switches can be closed at a time by cam plates 142 or 143. Switch 144 is connected in a circuit to be described later and shown in Fig. 24, which causes height-adjusting motor 17 to operate to raise the vertically shiftable carriage 96, and switch 145 is in an electrical circuit which, when closed, causes motor 17 to operate to lower carriage 96.

Switches 144 and 145 are mounted upon a horizontal bar 146 which is slidably mounted in a stationary frame member at the top of posts 100, and is provided with rack teeth 147 which engage pinion teeth 148 formed on horizontal transverse shaft 107, the rotation of which by motor 17 causes the raising and lowering of rack bar 109 and hence the raising or lowering of carriage 96. Bar 146 and switches 144 and 145 are therefore shifted horizontally whenever the carriage 96 is shifted vertically, and the arrangement is such that the amount of horizontal movement of bar 146 is the same as the vertical movement of carriage 96. Switches 144 and 145 move to the left when carriage 96 is lowered and to the right when it is raised.

Assuming now that the carriage 96 is in its highest position, switches 144 and 145 will be in

the position shown in Fig. 8, and, since control setting bar 139 is in its extreme hand position corresponding to the highest case which the machine is adapted to handle, the ends of the actuating levers of switches 144 and 145 are between the opposed inner ends of cam plates 142 and 143 and both of switches 144 and 145 are therefore open.

As soon as a case reaches gauging position and gauging bar 121 is lowered by cam 134, the head piece 138 of setting bar 136 will be moved to the left and engage a collar 149 which is secured to control bar 139 and shift this bar to the left against the tension of spring 140 to some position between the H position and the L position shown in Fig. 9, unless the case is one of maximum height, in which event the head piece 138 merely touches the collar 149 but does not move it.

Assuming, for example, that the case entering the machine is one having a height M_1 , then the head piece 138 will engage collars 149 and shift bar 139 to the left until the collar reaches the full line position shown at M_1 in Fig. 9. This also moves cam plates 142 and 143 and collar 141 to the left, and the engagement of cam plate 143 with the end of the operating lever of switch 145 causes the contacts of this switch to be closed and held in closed position. This does not, however, cause motor 17 to be operated because the preceding case might still be beneath the carriage 96, and should this case have been one of a height greater than M_1 , the downward movement of carriage 96 would either injure the case or cause damage to the machine. Control setting bar 139 is held in position M_1 by a spring actuated latch 150 which engages a series of latch teeth 151 on the side of bar 139. This latch is mounted on the left hand side of bracket 128. Head piece 138 can therefore immediately recede from engagement with collar 149 as the gauging bar 121 rises away from the case and leaves control bar 139 latched in the maximum position to which it was shifted toward the left, in this case, position M_1 .

The next event to occur is the closing of two cam operated switches 152 and 153 (see Figs. 24, 14 and 1a). These switches are like switches 144 and 145 except that they are actuated by rotating cams 154 and 155 which are so set on their operating shaft 156 as to close the two switches simultaneously. Shaft 156 is driven by a chain 157 and suitable sprockets from main camshaft 68. These cams are so timed as to close switches 152 and 153 as soon as the preceding case has been advanced beyond the gluing mechanism carriage 96 by one of the drive bars 10. If the operation of the gauging mechanism 14 has caused the closing of one or the other of switches 144 or 145 in the manner described above, then when cam-operated switches 152 and 153 are closed, motor 17 is energized to either raise or lower the carriage 96.

As shown in Fig. 24 (lower portion), the power supply is from line conductors 158 to a relay 159, the main contacts of which are connected through conductors 159a to the leads of motor 17 to operate this motor in a direction to cause carriage 96 to be lowered. The current passes through a conductor 160 in which is located a stop and start push button switch 160a to cam operated switch 153, and under the conditions shown in Fig. 9 where control switch 145 is closed by cam plate 143, the closing of cam-operated switch 153 causes current to flow through conductor 161 to control switch 145, and

thence through conductor 162 to down limit switch 163. From switch 163 current passes through conductor 164 to the operating coil 159b of relay 159. A conductor leads the current from this coil back to one of the supply conductors 158. The energizing of coil 159b causes the relay to be lifted to closed position, thus energizing motor 17. Relay 159 carries a pair of holding circuit contacts 159c which close a circuit in shunt to, or by passing cam operated switch 153, so that it is necessary for cam 155 to close this switch only momentarily. Hence motor 17 will continue to operate to lower carriage 96 until either control switch 145 or limit switch 163 opens the circuit.

A magnetic brake 165 that operates on the motor shaft is provided with an operating coil which is connected across the terminals of the motor so that whenever the motor is energized the brake operating coil is also energized and the brake released. This brake operates in a well understood manner and by means of a spring causes the brake to stop the motor instantly when the motor and brake-operating coil are de-energized.

Should control switch 144 be closed instead of switch 145, motor 17 will be operated in the opposite direction so as to raise carriage 96 through the lifting to closed position of a second relay 269 whose operating coil is indicated at 270. Current to this operating coil is controlled in a similar manner to the current to operating coil 159b of relay 159, namely, by means of cam-operated switch 152, control switch 144 and limit switch 166, all of which are in series with each other and receive their current through the start and stop push button switch 160a.

Limit switches 163 and 166 have operating levers actuated by means of a finger 167 (Fig. 6) mounted on a part of carriage 96 so as to move up and down with it. These switches open the circuit of motor 17 and stop its operation in case the control mechanism should not function properly.

Returning now to the consideration of Figs. 8-12, inclusive, the operation of the control mechanism had progressed to the point where, after the setting of bar 139 in the position shown in Fig. 9, thereby causing cam plate 143 to close "down" switch 145, the cam operated switches 152 and 153 had been closed, causing motor 17 to commence moving carriage 96 downward. As this movement occurs, bar 146 carrying switches 144 and 145 commences to move toward the left from its original position shown in Fig. 9. As this movement takes place, the roller on the end of the operating lever of switch 145 rolls along the surface of cam plate 143 until it reaches the left hand end of this cam plate, at which instant the roller is released and the operating lever moves outwardly, thereby opening the contacts of switch 145 and stopping motor 17 instantly through the application of the solenoid brake 165. This operation of the motor has lowered carriage 96 to the height M_1 as shown in Fig. 7.

As soon as carriage 96 has been lowered to position M_1 the spring held latch 150 is released from the teeth 151 at the left hand end of control bar 139 and this bar is returned to its original position, shown in Fig. 8, by the tension of spring 140, where collar 141 is against the frame member in which the right hand end of the bar 139 slides. This positions control bar 139 for the

next operation of the case-gauging mechanism 14.

The release of latch 150 is effected by the operation of a lever 168, the upper end of which engages the tail portion 169 of latch 150 and rocks the latch on its pivot. Lever 168 is actuated by a link member 170 connected at its lower end to a lever 171 pivoted on frame member 2 at 172 and having a roller 173 which engages the surface of a large disc cam 174 on main cam shaft 68 adjacent cam 134. The roller is held in contact with the cam, and lever 168 normally held out of engagement with latch 150, by means of a helical spring 175.

During the operation of motor 17 to readjust the height of carriage 96, the case has been advanced by one of the drive bars 10 from the gauging mechanism 14 until it is now on platen 6 and substantially in the position shown in dotted lines in Fig. 2b ready to enter the flap gluing and folding mechanism 16.

The gauging and gluing of the case having a height M_1 , just referred to, has left bar 146 and control switches 144 and 145 in the position shown in Figs. 10 and 11. Assuming now that a case of height M_2 is delivered by the timing mechanism 11 to the gauging position, in the descent of the gauging bar 121, it will be stopped in a higher position. Consequently setting bar 136 will not be moved so far to the left as before, and control bar 139 will be stopped and latched by latch 150 in position M_2 (Fig. 11). Hence the switch operating cam plates 142 and 143 also will not be moved so far to the left, but will be stopped in the position shown in Fig. 11 with cam plate 142 coacting with the operating lever of up-switch 144 to hold this switch closed. Therefore upon the closing of cam switch 152 by the rotation of shaft 156, a circuit will be established to operate motor 17 in the opposite direction from its previous operation and raise the carriage 96. This movement continues until bar 146 and switches 144 and 145 have been moved to the right to the position shown in Fig. 12 where the operating lever of switch 144 has been released by cam plate 142, thereby opening the switch contacts and stopping motor 17. In this way carriage 96 has been adjusted by raising it slightly to the position M_2 (Fig. 2b) and the flap unfolding and closing mechanism carried by the carriage are now in position to operate upon the higher case.

It will be understood that these operations are repeated whenever a case is delivered to the machine which is of a different height from the preceding case. If two or more cases of the same height are delivered to the gauging position successively, the gauging mechanism 14 operates as before to shift control bar 139 to the left from its reference point the same distance for each case, this bar always being released by the latch 150 after a gauging operation and returned to the right to its original reference point position with collar 141 against the adjacent frame member. Motor 17, however, will not be operated when successive cases of the same height are admitted, except at the gauging of the first case of the series.

This is unnecessary because the gluing mechanism carriage 96 is at the right height for the successive cases after the first, and the operation of the motor is prevented inasmuch as the successive movements of control bar 39 leave the cam plates 142 and 143 always centered with respect

to the switch-actuating levers, in which position both of switches 144 and 145 are open.

When the machine is operating on boxes of either the minimum height L or the maximum height H, motor 17 is still under the control of switches 144 and 145; that is to say, the operation of the motor is stopped by these switches rather than by the limit switches 163 or 166, the purpose of the limit switches being to stop the motor only in the event that the carriage 96 is moved below the L position or above the H position.

Referring now more particularly to Figs. 17-20, 15 and 2a, the operation of the control mechanism for the width adjustment of the gluing mechanism will now be described. As a carton leaves the gauging position 14 and is pushed by one of the driving bars 10 toward the gluing mechanism, it enters between two centralizing guide bars 176 and 177 which are flared outwardly as shown in Figs. 17 and 1a. These guide bars are laterally movable and are arranged to move toward one another in timed relation to the passage of each driving bar 10 over roller table 4.

As the guides move toward one another while the case is on table 4, the case is centered in the machine. The guides remain in this position in contact with the opposite sides of the case until the case is received within the gluing mechanism 16 and between the lower and upper guides 76 and 76a of this mechanism (Fig. 6).

Guide bar 176 is supported, in part, by a pair of arms 178 which are fixed to a longitudinal shaft 179 at their lower ends, and at their upper ends are connected to brackets 180 attached to the sides of the guides, and, in part, by a pair of horizontal rods 181 which slide in brackets 182 mounted on said frame member 1. Guide bars 177 are similarly supported, in part, by two parallel rods 181a fixed at their inner ends to the guide bar and slidably near their outer ends in brackets 182a mounted upon frame member 2. They are also, in part, supported by two upwardly extending arms 178a fixed at their lower ends to a longitudinal shaft 179a and connected at their upper ends to brackets 180a which are attached to the sides of the guide bars 177.

Elongated helical springs 183 surround each of the two pairs of rods 181 and 181a and urge the guide bars 176 and 177 inwardly against the sides of the case passing between them. The guide bars are moved outwardly against the pressure of these springs by the rocking of longitudinal shafts 179 and 179a in opposite directions simultaneously, by the mechanism shown in Fig. 17 and Figs. 2a and 1a. This comprises a pair of short arms 184 that are fixed to shafts 179 and 179a and have rollers 185 which are engaged by a transversely extending yoke member 186.

This yoke member is supported at each end by means of a pair of rock arms 187 which are fixed to a rock shaft 188 carried in brackets beneath and secured to the side frames 1 and 2. Rock shaft 188 is adjacent main cam shaft 68 and one of the rock arms 187 has an extension 189 to which a roller 190 is pivoted for engagement with a cam 191 on main cam shaft 68. It will be understood that the rotation of cam 191 actuates rock shaft 188 and causes rock arms 187 to be raised and lowered and with them the yoke 186, thereby simultaneously rocking the longitudinal shaft 179 and 179a and hence moving the guides 176 and 177 toward or away from one another.

These guide bars 176 and 177 serve, not only to guide the cartons, but also as a gauging de-

vice for gauging the width of the carton and for controlling the width-adjusting motor 18 of the gluer width-adjusting mechanism. As previously explained in connection with Fig. 6, both the lower and upper assemblies 84 and 84a are power-adjusted to place the glue rollers in proper position for applying the adhesive to the flaps of the case. These assemblies also carry the upper and lower guides 76 and 76a and the flap unfolders 77 and 77a.

The width-adjusting mechanism differs from the height-adjusting mechanism in that the assemblies 84 and 84a are not adjusted to the exact width of each case coming through the machine, but are adjusted only to either of two positions, an inner position for cases narrower than a predetermined width and an outer position for cases wider than that width. The reason for this is that where cases differing considerably in width follow one another into the machine, it would slow down the output of the machine if the assemblies 84 and 84a were accurately adjusted into contact with the sides of each case. Furthermore such accurate adjustment is unnecessary as the lower guides 76 and 76a and the flap unfolders 77 and 77a operate entirely satisfactorily even though they are not accurately and closely adjusted for each case.

The stopping of the operation of the width-adjusting motor 18 when the assemblies 84 and 84a have been adjusted to either the inner or outer positions is accomplished by limit switches instead of by control switches as in the case of the height-adjusting mechanism. These limit switches are shown at 192 and 193 for the lower assembly 84 and are actuated by a finger 194 carried by this assembly. Limit switches 195 and 196 are actuated by a finger 197 carried by the upper assembly 84a.

The control mechanism is similar, in its principle of operation, to the control mechanism described in connection with Figs. 8-14, inclusive, for the height adjustment, but differs in that the width-gauging members (guides 176 and 177) are left in contact with the sides of the case, whereas the gauging bar 121 is only momentarily brought into contact with the top of the case and then immediately retracted so as to permit the case to pass beneath it without interference with the case flaps.

The starting of the width-adjusting movement by the energization of width motor 18 is accomplished by a pair of in-and-out or width control switches 198 and 199 (Figs. 15, 18, 19, 20 and 1b) which are mounted upon a bracket on lower guides 176 on the left hand side of the machine when facing the entrance end. The positions of the actuating levers of these switches are controlled by cam plates 200 and 201 similar to cam plates 142 and 143 and mounted upon a bracket which projects outwardly from side guide bar 176. As in the case of the height-control mechanism, cam-operated switches 202 and 203 are provided for the width control. These are operated by cams 204 and 205 on the same shaft 156 as cams 154 and 155 for the height control mechanism.

Referring to the wiring diagram, Fig. 24 (upper portion) two relays are provided for connecting motor 18 with the power supply line 158. Relay 271 operates the motor to make the gluing mechanism assemblies 84 and 84a move inward toward one another, and relay 272 operates this motor to move the assemblies outward or away from each other.

The operating coil 273 of relay 271 is energized

when the "in" cam switch 202, control switch 198 and limit switches 192 and 195, all of which are in series, are all closed. The current flows from one line conductor 158 to a start and stop push button switch 274 through conductors 275 and 276 to "in" cam switch 202, thence to control switch 198 and thence through conductor 277, to the limit switches and then to operating coil 273 and back to one of the other line conductors 158.

Upon the closing of the contacts of relay 171 a pair of holding contacts 278 close a holding or bypass circuit from conductor 275 through conductor 279 and to conductor 277 around both the "in" cam-operated switch 202 and the "in" control switch 198. Hence both of these switches need be closed only momentarily. This enables the side guide or gauging bars 176 and 177 to be moved outwardly for a succeeding case entering the machine before the width adjustment of assemblies 84 and 84a with their guides 76 has been completed by motor 18.

The "out" switches, namely, cam switch 203, control switch 199 and limit switches 193 and 196 are connected in series with the operating coil 279 of relay 276 in an exactly similar manner to that just described in connection with the "in" switches, as is apparent from Fig. 24. Also relay 275 has at the bottom a pair of holding contacts 280 which close a holding circuit around "out" cam switch 203 and "out" control switch 199 exactly as described in connection with holding contacts 278 of relay 271. The control of width motor 18 is therefore exactly the same for the outward movement of the assemblies 84 and 84a as for the inward movement.

An electromagnetic brake 206 operates on the shaft of width motor 18 and is connected across the motor terminals so as to be energized whenever the motor is energized, the same as the electromagnetic brake 165 for the height motor 17.

Referring to Figs. 18 and 19, the operation of the width motor control mechanism is somewhat like that described in connection with Figs. 8-14, inclusive. Assuming, for example, that a "narrow" case has passed through the machine, the assemblies 84, 84a and guides 76 and 76a will be in their inward position indicated in Fig. 18, and should a "wide" case now be presented to the machine, when the guide bars 176 and 177 are moved from their outermost positions against the sides of this case, they will be stopped in the position shown, for example, in Fig. 19. In that position the cam plate 200 engages the operating lever of the out-control switch 199 and holds the contacts of this switch closed. Then, as soon as the cams 204 and 205 operate to close the switches 202 and 203, a circuit will be completed by the closing of switch 203 which will cause motor 18 to operate and commence to move the assemblies 84 and 84a including guides 76 outwardly away from one another.

The adjusting movement of assemblies 84 and 84a is stopped not by the release of "out" control switch 199 from cam plate 200, but by the opening of the lower and upper "out" limit switches 193 and 196 which places the assemblies 84 and 84a in the "wide" position. In view of the bypassing of "out" cam switch 203 and "out" control switch 199 through the closing of holding contacts 280 on relay 279, the centralizing gauging bars 176 and 177 (bar 176 carrying cam plates 200 and 201 for the control switches) can begin to move outwardly to receive the next case entering the machine as soon as "out" cam switch

203 closes. In this way the machine is enabled to handle a larger number of cases per minute since the movement of centralizing guides 176 and 177 to receive the next case does not have to await the completion of the adjustment of assemblies 84 and 84a.

The carton leaves the gluing mechanism 16 with its top and bottom side flaps extending outwardly in horizontal position and with moist adhesive applied to their upper and lower surfaces respectively. The mechanism to the left of gluing mechanism 16 (Fig. 2b) refolds the outer case flaps to closed position and presses them into sealing engagement with the inner flaps while the case moves forward under the action of driving bar 18. This mechanism comprises the top refolders 207 (Fig. 15), each of which is carried by a forked arm 208, and the bottom refolders 209 (Fig. 16) which are bolted to guide bars 210. It also comprises an elongated pressing shoe 211 for holding down the top inner flaps and a spring pressed sealing shoe 212 for forcing the outer flaps into sealing engagement with the inner flaps. These members are all automatically adjusted to suit the width and height of each particular case which is fed to them.

The top and bottom flap refolders 207 and 209 together with the guides 210 are adjusted laterally to suit the width of the case and, in addition, the top refolders 207 and the two flap-engaging shoes are adjusted vertically to suit the height of the case. This adjusting mechanism is shown in Figs. 21-23, 1b and 2b. The guides 210 which support bottom flaps 209 are secured to the inner ends of two sets of parallel horizontal rods 213 and 214. At their outer ends rods 213 are clamped fast in brackets 215 and rods 214 are similarly clamped in brackets 216. Brackets 215 are secured fast on two vertical rods 217 and brackets 216 are secured fast on two vertical rods 218. The forked arms 208 which support the top flap refolders 207 are pivoted at 219 and 220, respectively, to brackets 221 and 222, respectively. Bracket 221 is clamped fast to vertical rod 217 above bracket 215 and bracket 222 is clamped fast to vertical rod 218 above bracket 216.

Vertical rods 217 and 218 are so mounted as to move bodily inwardly or outwardly, as indicated by the arrows in Fig. 21, thereby causing the desired adjustment of the top and bottom flap refolders 207 and 209 and the guides 210. To provide for this movement, rods 217 are each supported at the bottom and at the top by short equal length horizontal arms 223 fixed to two vertical shafts 224 which are mounted at their lower and upper ends for rocking movement in brackets (Figs. 15 and 21) secured to a fixed frame structure 225 which extends upwardly from side frame members 1 and 2 and across the top of the machine (Fig. 21).

Shafts 224 are caused to rock in unison by means of a link 226 which joins another pair of equal length arms projecting laterally from and fixed to these shafts. A large helical spring 227 connected at one end to one of the arms to which link 226 is connected, and at its opposite end to a fixed part of the machine frame, urges shafts 224 to rock in a direction to force rods 217 and the refolders 207 and 209, and the guide 210 carried thereby, toward the center of the machine.

At the opposite side of the machine (Figs. 15 and 16) the bodily movable vertical rods 218 are supported by mechanism like that just described and including two parallel vertical rock shafts 228 and 229 which are joined together for motion

in unison by means of a link 230 and are biased by means of a spring 231. These two sets of supporting mechanisms are connected together by means of a long link 232, on top of frame structure 225, which is pivoted at one end to an arm 233 on one of the rock shafts 224 and at its opposite end to an arm 234 fixed to a vertical shaft 229, so that the guides 210 and refolders 207 and 209 move together either toward or away from the side walls of the case passing along platen or table 6.

These carton guiding and flap folding devices are moved outwardly in timed relation to the advance of each case by means of a cam 235 (Figs. 21, 15 and 16) which engages a roller 236 mounted at the end of a short arm 237 fixed to the lower end of vertical shaft 229. Cam 235 is mounted on a transverse shaft 238 which is rotated by means of a sprocket 239, and chain 240, from a sprocket 241 on the outer end of cross shaft 7. Cam shaft 238 makes one revolution between the passage of successive guide bars 10.

The parts which are vertically adjusted including the inner flap-engaging shoe 211, the outer flap-closing shoe 212 and the upper flap refolders 207, are actuated for adjustment by mechanism which is shown particularly in Figs. 21-23 and also in Figs. 15, 1b and 2b. These parts are all carried on a vertically movable structure indicated generally by numeral 242 (Fig. 2b) which includes a horizontal supporting bar 243. The inner flap holding shoe 211 is supported immediately beneath this bar, and outer flap-closing shoe 212 is pivoted near the rear end of this bar and is biased downwardly by means of a spring 244. The pivoted forked arms 208 which carry the upper flap unfolders 207 are supported by hangers 245, each of which at its upper end has a roller 246 which rests on the upper surface of a transverse horizontal rod 247 along the surface of which the rollers 246 operate as the structure 242 is raised or lowered.

The structure 242 is supported by two parallel rack bars 248 which are attached at their lower ends to bar 243. The teeth of these rack bars engage pinion teeth formed in the surfaces of two parallel shafts 249 and 250. These two shafts are connected together for rotation in unison by means of a short chain 251 and suitable sprockets. Shafts 249 and 250 are rotatably supported in a downwardly extending bracket member 252 mounted at the center of the cross member of frame structure 225.

Shaft 250 extends to one side of the machine as shown in Figs. 21 and 15 where it is provided with pinion teeth 253 which engage a vertically movable rack rod 254. This rack rod is connected at its lower end to a lever 255 pivoted at 256 on the frame of the machine and having a roller 257 which cooperates with a cam 258. Cam 258 is mounted on the end of cam shaft 238, and in rotating raises lever 255 and rack rod 254 rotating shaft 250 and thereby raising the structure 242 and the several case contacting parts supported thereby.

When a case reaches gluing mechanism 16 and enters beneath structure 242, this structure is lowered by mechanism to be described presently until inner flap engaging shoe 211 rests upon the case and the entire structure is supported by the case. However, if the case nears the discharge end of the machine it is evident that the heavy structure 242 cannot be supported in this way. For the purpose of supporting structure 242 at this time a ratchet wheel 259 (Fig. 22) is provided

on shaft 250 and in engagement with its teeth there is a spring pressed holding pawl 260 pivoted at 261 and biased against the wheel by helical spring 262. During the raising movement of structure 242, this pawl clicks over the ratchet wheel teeth.

In the operation of adjusting the horizontally adjustable parts at the discharge end of the machine, including the guides 210, the flap reclosers 207 and 209; also the vertical adjusting of the shoes 211 and 212 and the flap reclosers 207, there is a cooperation of action between the horizontal and vertical adjusting mechanisms. As previously stated the cam 235 is timed to separate the laterally adjustable parts to the maximum extent and then to allow them to approach one another as each case leaves the gluing mechanism 16 and moves between the right hand end portions of the guides 210. Cam 258 is timed to elevate the vertically adjustable parts carried by structure 242 simultaneously with the separating movement of the laterally adjustable parts, and pawl 260 is withdrawn from ratchet wheel 259 by the outward movement of the lateral adjusting mechanism and just before the end of such outward movement. Hence during the continued rotation of cam 258, structure 242 is allowed to descend by gravity so as to operate in connection with the next case as it leaves the gluing mechanism 16.

The arrangement by which pawl 260 is tripped by the outward movement of the lateral adjusting mechanism is shown in Figs. 22 and 23. Pawl 260 is pivoted adjacent the upper portion of vertical rock shaft 228, and mounted on this rock shaft is a short arm carrying an upstanding finger 263 which, as the rock shaft turns in the direction of the arrow shown in Fig. 23, engages a projection 264 on the tail of pawl 260, thereby forcing the pawl out of engagement with the teeth of the ratchet wheel.

The vertically adjustable structure 242 is not lowered directly into contact with the next case, but during this lowering movement roller 257 follows cam 258 until a latch 265 (Fig. 2b) at the forward end of structure 242 engages a shoulder on gluer mechanism carriage 96. This latch is pivoted at 266 and biased by a helical spring 267. A tripping finger 268 is secured to the back of latch 265 and extends downwardly into the path of the case.

In the normal operation of the machine the structure 242 has been lowered and is supported by latch 265 before a case leaves gluing mechanism 16. Structure 242 has therefore been adjusted to the height of the oncoming case and is held at a position only slightly above the top of this case. As the case moves from beneath gluing mechanism 16 its forward edge strikes tripping finger 268, thereby releasing latch 265 and causing structure 242 to descend and rest upon the case. The case progresses beneath the flap refolding and closing mechanism carried by structure 242 and as the case nears the rear end of structure 242 the weight of this structure is shifted to ratchet and pawl mechanism 259, 260 as previously described.

As the rear end of the case passes just beyond the end of outer flap closing shoe 212, cam 258 again engages roller 257, and commences the elevation of structure 242 for the next case.

In this machine of my present invention there has been provided a carton-closing machine which is automatically self-adjustable to conform with the width and height dimensions of each in-

dividual case as it comes through the machine, all of the elements of the machine which require shifting in order that they may properly cooperate with or act upon the case being automatically adjusted to the proper operating positions. It will be understood that changes can be made in the various parts of the mechanism as illustrated in the drawings and described above without departing from the spirit or scope of the invention which is indicated in the accompanying claims.

I claim:

1. In a machine of the class described, an elongated case support, mechanism for performing a sealing operation on the flaps of a case, a vertically movable carriage for supporting said mechanism above the case support to operate on the top flaps of a case on said support, power-operated mechanism for raising or lowering said carriage, means for moving a case along said support and beneath said carriage, control mechanism for said power operated mechanism, a gauging member movable vertically with respect to said support, mechanism for actuating said gauging member into engagement with the top of a case on said support, means associated with said gauging member for setting the control mechanism to correspond with the height of said case, and means for causing said control mechanism to effect the operation of the power operated mechanism to raise or lower the carriage to correspond to the height of the case prior to the passage of the case beneath the same.
2. In a machine of the class described, an elongated case support, mechanism for performing a sealing operation on the flaps of a case, a vertically movable carriage for supporting said mechanism above the case support to operate on the top flaps of a case on said support, power-operated mechanism for raising or lowering said carriage, means for moving cases in spaced relation along said support and beneath and beyond said carriage, control mechanism for said power-operated mechanism, a gauging member movable vertically with respect to said support, mechanism for actuating said gauging member into engagement with the top of a case on said support, means associated with said gauging member for setting the control mechanism to correspond with the height of said case, and means for causing said control mechanism to effect the operation of the power-operated mechanism to raise or lower the carriage to correspond to the height of the case prior to the passage of the case beneath said carriage and subsequent to the passage of the preceding case beyond said carriage.
3. In a machine of the class described, an elongated case support, mechanism for performing a sealing operation on the flaps of a case, a vertically movable carriage for supporting said mechanism above the case support to operate on the top flaps of a case on said support, power-operated mechanism for raising or lowering said carriage, feeding means for feeding cases successively to a gauging station on said support, control mechanism for said power-operated mechanism, a gauging member movable vertically with respect to said support at said gauging station, mechanism for actuating said gauging member into engagement with the top of a case at said station, means associated with said gauging member for setting the control mechanism to correspond with the height of said case, means for causing said control mechanism to effect the operation of the power-operated mechanism to

raise or lower the carriage to correspond to the height of the case, and a second feeding means for advancing the case from the gauging station along said support and beneath said carriage to cause the sealing operation to be performed on the case.

4. In a machine of the class described, an elongated case support, mechanism for performing a sealing operation on the flaps of a case, a vertically movable carriage for supporting said mechanism above the case support to operate on the top flaps of a case on said support, power-operated mechanism for raising or lowering said carriage, control mechanism for said power-operated mechanism, a gauging member movable vertically with respect to said support, actuating mechanism for lowering said gauging member into momentary engagement with the upper edge of a wall of a case on said support and raising the gauging member out of the path of the up-standing flaps of the case to permit it to be advanced along said support, a control member adapted to be set at a plurality of positions to predetermine the direction and extent of movement of said power operated mechanism, setting means associated with the gauging member actuating mechanism for moving the control member to a predetermined position corresponding to the position of the gauging member when in contact with the case, means for causing the control mechanism to effect the operation of the power-operated mechanism to raise or lower the carriage to the extent corresponding to the position of said control-setting member, and means for moving the case along said support beneath said carriage to cause the sealing operation to be performed on the case.

5. In a machine of the class described, an elongated case support, means for feeding cases successively along said support, two carriages adjustable laterally relative to one another and disposed one on each side of said support, gluing mechanism on said carriages for applying adhesive to the side flaps of a case passing along said support between the carriages, power-operated mechanism for moving the carriages in either direction relative to one another to effect the said lateral adjustment thereof to bring the gluing mechanism into proper position to operate upon the flaps of a case to be glued, control mechanism for said power-operated mechanism, a pair of guides adjustable laterally relative to one another and disposed one on each side of said elongated support to guide the case therealong before it reaches the gluing mechanism, means for actuating said guides into engagement with the sides of a case on said support, and a control-setting member actuated by one of said guides for causing the control mechanism to effect the operation of the power-operated mechanism in the desired direction and to the extent required to adjust said carriages to bring the gluing mechanism thereon into proper position to operate on said case.

6. In a machine of the class described, an elongated case support, mechanism for performing a sealing operation on the flaps of a case, a carriage for supporting said mechanism to operate on the flaps of a case on said support, mechanically operated mechanism for moving said carriage, means for moving a case along said support and past said carriage, control mechanism for said mechanically operated mechanism, a gauging member, mechanism for actuating said gauging member into engagement with a case

5 on said support, means associated with said gauging member for setting the control mechanism to correspond with a dimension of said case and means for causing said control mechanism to effect the operation of the mechanically operated mechanism to move the carriage to correspond with such dimension of the case prior to the passage of the case past the same.

7. In a machine of the class described an elongated case support, mechanism for performing a sealing operation on the flaps of a case, a carriage for supporting said mechanism to operate on the top flaps of a case on said support, mechanically operated mechanism for moving said carriage, means for moving a case along said support and past said carriage, control mechanism for said mechanically operated mechanism, a gauging member, mechanism for actuating said gauging member into engagement with a case on said support, means associated with said gauging member for setting the control mechanism to correspond with a dimension of said case and means for causing said control mechanism to effect the operation of the mechanically operated mechanism to move the carriage to correspond with such dimension of the case prior to the passage of the case past said carriage and subsequent to the passage of the preceding case beyond said carriage.

8. In a machine of the class described an elongated case support, mechanism for performing a sealing operation on the flaps of a case, a carriage for supporting said mechanism to operate on the top flaps of a case on said support, mechanically operated mechanism for moving said carriage, feeding mechanism for feeding cases successively to a gauging station on said support, control mechanism for said mechanically operated mechanism, a gauging member, mechanism for actuating said gauging member into engagement with a case at said station, means associated with said gauging member for setting the control mechanism to correspond with a dimension of said case, means for causing said control mechanism to effect the operation of the mechanically operated mechanism to move the carriage to correspond with such dimension of the case and a second feeding means for advancing the case from the gauging station along said support and past said carriage to cause the sealing operation to be performed on the case.

9. In a machine of the class described, an elongated case support, mechanism for performing a sealing operation on the flaps of a case, a carriage for supporting said mechanism to operate on the top flaps of a case on said support, mechanically operated mechanism for moving said carriage, control mechanism for said mechanically operated mechanism, a gauging member, actuating mechanism for moving the gauging member into momentary engagement with a case on said support and withdrawing the same, a control member adapted to be set at a plurality of positions to predetermine the direction and extent of movement of said mechanically operated mechanism, setting means associated with the gauging member actuating mechanism for moving the control member to a predetermined position corresponding to the position of the gauging member when in contact with the case, means for causing the control mechanism to effect the operation of the mechanically operated mechanism to move the carriage to the extent corresponding to the po-

sition of said control member and means for moving the case along said support past said carriage to cause the sealing operation to be performed on the case.

10. In a machine of the class described, an elongated case support, mechanism for performing a sealing operation on the flaps of a case, a carriage for supporting said mechanism to operate on the flaps of a case on said support, mechanically operated mechanism for moving said carriage, means for moving a case along said support and past said carriage, a gauging member, mechanism for actuating said gauging member into engagement with a case on said support to gauge a dimension of the case and mechanism associated with the gauging member for causing said mechanically operated mechanism to move the carriage to correspond with the gauged dimension of the case.

11. In a machine of the class described an elongated case support, mechanism for performing a sealing operation on the flaps of a case, a carriage for supporting said mechanism to operate on the top flaps of a case on said support, mechanically operated mechanism for moving said carriage, feeding mechanism for feeding cases successively to a gauging station on said support, a gauging member, mechanism for actuating said gauging member into engagement with a case at said station to gauge a dimension of the case, mechanism associated with said gauging member for causing said mechanically operated mechanism to move the carriage to correspond with the gauged dimension of the case and a second feeding means for advancing the case from the gauging station along said support and past said carriage to cause the sealing operation to be performed on the case.

12. In a machine of the class described, the combination with an adjustable sealing mechanism and means for conveying cases past said mechanism, of a gauging device for gauging a dimension of a case and mechanism operatively responsive to said gauging device for adjusting the sealing mechanism to correspond with said case dimension prior to the passing of the case into engagement with said sealing mechanism.

13. In a machine of the class described, an elongated case support, vertically adjustable case sealing mechanism associated with said support, said support having a withdrawable stop near the front end thereof, means for feeding cases one at a time against said stop, a case gauging device operable to gauge the height of the case while it is held by the stop, case advancing means for moving the case along the support past the sealing mechanism, means for withdrawing the stop and mechanism responsive to the operation of said gauging device for causing the adjustment of the sealing mechanism to correspond with the height of the case.

14. In a machine of the class described, an elongated case support, vertically adjustable case sealing mechanism associated with said support, said support having a withdrawable stop near the front end thereof, means for feeding cases one at a time against said stop, a case gauging device operable to gauge the height of the case while it is held by the stop, case advancing means for moving the case along the support past the sealing mechanism, means for withdrawing the stop and mechanism controlled by said gauging device and operable while the case is advancing from said stop to said sealing mechanism to cause

an adjustment of the sealing mechanism to correspond with the height of the case.

15. In a machine of the class described, an elongated case support, vertically adjustable case sealing mechanism associated with said support, positive case advancing means for moving cases one at a time along the support past the sealing mechanism, said support having a withdrawable stop near the front end thereof, means for feeding cases one at a time against said stop in timed relation to said positive case advancing means, a case gauging device for gauging the height of the case while held by said stop, means for withdrawing the stop in timed relation to the operation of said positive advancing means, and mechanism responsive to the operation of said gauging device for causing the adjustment of said sealing mechanism to correspond with the height of the case.

20. 16. In a machine of the class described, the combination with an adjustable sealing mechanism and means for conveying cases past said mechanism of gauging mechanisms for gauging two dimensions of a case and mechanism operatively responsive to each of said gauging mechanisms for adjusting the sealing mechanism as to each of said case dimensions prior to the passing of the case into engagement with said sealing mechanism.

30. 17. In a machine of the class described, the combination with an adjustable sealing mechanism and means for conveying cases past said mechanism of a gauging device for gauging the height of a case, a gauging device for gauging the width of the case and mechanism operatively responsive to each of said gauging devices for adjusting the sealing mechanism prior to the passing of the case into engagement with said sealing mechanism.

40. 18. In a machine of the class described, the combination with vertically and laterally adjustable sealing mechanism and means for conveying cases past said mechanism, of a gauging device for gauging the height of a case, a gauging device for gauging the width of the case, mechanism operatively responsive to said height-gauging device for adjusting the sealing mechanism to correspond with the case height and mechanism operatively responsive to said width-gauging device for adjusting the sealing mechanism to an inner position for cases narrower than a predetermined width and to an outer position for cases wider than said width.

55. 19. In a machine of the class described, an elongated case support, a sealing mechanism adjustable laterally to perform a sealing operation upon successive cases of different width, means for conveying cases along said support past said mechanism for sealing, and positively actuated centering mechanism mechanically operated in timed relation to said conveying means to deliver each case to the sealing mechanism accurately centered with respect thereto.

65. 20. In a machine of the class described, an elongated case support, a laterally adjustable sealing mechanism adapted to perform a sealing operation upon successive cases of different width, means for conveying cases along said support past said mechanism for sealing, and centering mechanism to deliver each case to the sealing mechanism accurately centered with respect thereto, said mechanism comprising a pair of parallel guide bars for coacting with the opposite sides of the cases moved along the support by the conveyor, devices connected thereto to

maintain the bars in parallel relation and permit lateral movement thereof with respect to said support and mechanically operated means for simultaneously separating said bars and causing them to approach one another in timed relation to the advance of each case between them on said support by the conveying means.

21. In a machine of the class described, an elongated case support, a laterally adjustable sealing mechanism adapted to perform a sealing operation upon successive cases of different width, means for conveying cases along said support past said mechanism for sealing, and centering mechanism to deliver each case to the sealing mechanism accurately centered with respect thereto, said centering mechanism comprising a pair of parallel guide bars for coacting with the opposite sides of the cases moved along said support by the conveyor, devices connected thereto to maintain the bars in parallel relation and permit lateral movement thereof with respect to said support, means for yieldingly urging said bars toward one another and mechanism mechanically operated in timed relation with the advance of each case between said bars to separate them beyond the width of the widest case prior to the entry of the case between them and then allowing the bars to be moved into engagement with the case by said yielding means.

22. In a machine of the class described, an elongated case support, a laterally adjustable sealing mechanism adapted to perform a sealing operation upon successive cases of different width, means for conveying cases along said support past said mechanism for sealing, positively actuated centering mechanism to move a case laterally on said support to deliver each case to the sealing mechanism accurately centered with respect thereto, said mechanism being operated in timed relation to said conveying means, and mechanism operatively responsive to said centering mechanism for adjusting the sealing mechanism to an inner position for cases narrower than a predetermined width and to an outer position for cases wider than said width.

23. In a machine of the class described, an elongated case support, a laterally adjustable sealing mechanism adapted to perform a sealing operation upon successive cases of different width, means for conveying cases along said support past said mechanism for sealing, positively actuated centering mechanism to move a case laterally on said support to deliver each case to the sealing mechanism accurately centered with respect thereto, said mechanism being operated in timed relation to said conveying means, and mechanism operatively responsive to said centering mechanism for adjusting the sealing mechanism inwardly or outwardly a predetermined distance pursuant to a change in case width less or greater than a predetermined width dimension.

24. In a machine of the class described, vertically and laterally adjustable upper and lower flap-adhesive-applying mechanisms, a gauging device for gauging the height of a case, a gauging device for gauging the width of the case, mechanism operatively responsive to each of said gauging devices for adjusting the adhesive-applying mechanism vertically and laterally to correspond with the height and width of the case, upper and lower flap closing devices, the said upper devices being both vertically and laterally adjustable and the said lower devices being laterally adjustable, means for conveying cases past

said mechanisms for sealing, means operated in timed relation to said conveyor for adjusting said upper and lower flap closing devices laterally and means operated in timed relation with said conveyor for adjusting the upper flap-closing devices vertically.

25. In a machine of the class described, an elongated case support, upper and lower flap adhesive-applying mechanism laterally adjustable to operate upon successive cases of different width, upper and lower laterally adjustable flap-closing mechanism, means for conveying cases one at a time along said support past said mechanisms for sealing, a gauging device for gauging the width of a case, mechanism operatively responsive to said gauging device for simultaneously adjusting the upper and lower adhesive-applying mechanisms inwardly or outwardly a predetermined distance pursuant to a change in case width less or greater than a predetermined width dimension and means operated in timed relation with said conveyor for simultaneously adjusting said upper and lower flap-closing devices to correspond with the width of each case passing into engagement with them.

26. In a machine of the class described, an elongated case support, flap-adhesive applying mechanism laterally adjustable to operate upon successive cases of different width, laterally adjustable flap-closing mechanism, means for conveying cases one at a time along said support past said mechanisms for sealing, a gauging device for gauging the width of a case, mechanism operatively responsive to said gauging device for adjusting the adhesive-applying mechanism inwardly or outwardly a predetermined distance pursuant to a change in case width less or greater than a predetermined width dimension and means operated in timed relation with said conveyor for adjusting said flap-closing devices to correspond with the width of each case passing into engagement with them.

27. In a machine of the class described, an elongated case support, vertically adjustable flap adhesive-applying mechanism associated with said support, vertically adjustable flap-closing mechanism also associated with said support, means for conveying cases one at a time along said support past said mechanisms for sealing, mechanism for adjusting the adhesive applying mechanism to correspond with the height of the case prior to the passing of the case into engagement with said adhesive applying mechanism and means for elevating the flap-closing mechanism and lowering the same onto the top of each case as it passes beneath the same.

28. In a machine of the class described, an elongated case support, a vertically adjustable flap adhesive-applying mechanism associated with said support, vertically adjustable flap-closing mechanism also associated with said support, conveying means for advancing cases one at a time along said support past said mechanisms for sealing, mechanism for adjusting said adhesive applying mechanism to correspond with the height of a case prior to the passing of the case into engagement with said mechanism, means for elevating and lowering the flap closing mechanism in timed relation to the conveying means, latch mechanism for arresting the downward movement of said mechanism substantially at the height to which the adhesive-applying mechanism has been adjusted, and means actuated by the case as it enters beneath the flap-closing

means to release said latch and permit said mechanism to settle onto the top of the case.

29. In a machine of the class described having an elongated case support and means for conveying cases along said support for sealing, a laterally adjustable flap-closing mechanism comprising a pair of case guides disposed one near each side of said support and a pair of flap-closing devices similarly disposed, parallel motion mechanisms one on each side of said support, each of said mechanisms supporting one of said guides and one of said flap closers, means for interconnecting said parallel motion mechanisms to cause the guides and flap closers to simultaneously approach or recede laterally with respect to said support, and mechanism actuated in timed relation to the conveying means to cause said guides and flap closers to separate beyond the width of the widest case for which the machine is adapted and then approach into operative engagement with each case as it moves along said support.

30. In a machine of the class described having an elongated case support and means for conveying cases along said support for sealing, a laterally adjustable flap-folding mechanism comprising a pair of laterally movable supporting structures one arranged on each side of said case support, means for biasing said supporting structures inwardly towards said case support, each of said structures having secured thereto a flap-closing device and a horizontal member for engaging the side wall of a case on said case support, said horizontal member serving simultaneously to guide one side of the case and to position the flap-closing device laterally with respect to the case.

31. In a machine of the class described having an elongated case support and means for conveying cases along said support for sealing, a laterally adjustable flap-folding mechanism comprising a pair of laterally movable supporting structures one arranged on each side of said case support, means for biasing said supporting structures inwardly towards said case support, each of said structures having secured thereto a flap-closing device and a horizontal member for engaging the side wall of a case on said case support, said horizontal member serving simultaneously to guide one side of the case and to position the flap-closing device laterally with respect to the case, and mechanism actuated in timed relation to the conveying means to cause said guides and flap closers to separate beyond the width of the widest case for which the machine is adapted and then approach into operative engagement with each case as it moves along said support.

32. In a machine of the class described having an elongated case support and means for conveying cases along said support for sealing, a pair of laterally and vertically movable flap-closing devices one arranged on each side of said case support, means for biasing said flap-closing device both inwardly and downwardly toward said case support, mechanism actuated in timed relation to said conveying means for retracting said flap-closing devices both laterally and vertically beyond the width and height of the maximum size of case for which the machine is adapted and causing them to approach each case as it is advanced by the conveying means, means operatively connected with said flap-closing devices for engaging the sides of the case to position said devices laterally with respect to the case

and means operatively connected with said devices for engaging the top of the case to position them vertically, so as to cause said devices to close the case flaps as it is advanced along said support.

33. In a machine of the class described having an elongated case support and means for conveying cases along said support for sealing, a pair of laterally and vertically movable flap closing devices one arranged on each side of said case support, mechanism actuated in timed relation to said conveying means for retracting said flap-closing devices both laterally and vertically beyond the width and height of the maximum size of case for which the machine is adapted and causing said devices to approach each case as it is advanced by the conveying means, means operatively connected with said flap-closing devices for engaging the sides of the case to position said devices laterally with respect to the case and means operatively connected with said devices for engaging the top of the case to position them vertically, so as to cause said devices to close the case flaps as it is advanced along said support.

34. In a machine of the class described, an adjustable sealing mechanism, means for conveying cases past said mechanism for sealing, a gauging device for gauging a dimension of a case comprising a reciprocable gauging member and means for actuating said member into yielding engagement with said case, contact with the case arresting the movement of the gauging member, and mechanism operatively responsive to said gauging member for adjusting the sealing mechanism to correspond with the said dimension of the case prior to the passing of the case into engagement with said sealing mechanism.

35. In a machine of the class described, an elongated case support, mechanism for performing a sealing operation on the flaps of a case adjustable to operate upon successive cases of different size, mechanically operated mechanism for adjusting said sealing mechanism, control mechanism for said mechanically operated mechanism, a gauging member, actuating mechanism for moving the gauging member into momentary engagement with a case on said support and withdrawing the same, a control member adapted to be set at a plurality of positions to predetermine the direction and extent of adjustment of said sealing mechanism, setting means associated with the gauging member actuating mechanism for moving the control member to a predetermined position corresponding to the position of the gauging member when in contact with the case, means for causing the control mechanism to effect the operation of the mechanically operated mechanism to adjust the sealing mechanism to the extent corresponding to the position of said control member and means for moving the case along said support past said sealing mechanism to cause the sealing operation to be performed on the case.

36. In a machine of the class described having an elongated support and means for conveying cases along said support for sealing, adjustable sealing mechanism and control mechanism for controlling the adjusting movement of said sealing mechanism comprising a control member biased to a fixed reference point position and adapted to be moved to a plurality of control positions to predetermine the direction and extent of adjustment of said sealing mechanism, a case gauging member, means for reciprocating the

gauging member into momentary engagement with a case on said support from a position beyond the maximum size of case for which the machine is adapted, control member setting means actuated to move proportionately to the movement of the gauging member and means interconnecting said setting means and the control member to cause movement of the control member away from its fixed reference position to commence when the gauging member in moving toward a case to be gauged reaches a position corresponding to the maximum size of case.

37. In a machine of the class described having an elongated support and means for conveying cases along said support for sealing, adjustable sealing mechanism and control mechanism for controlling the adjusting movement of said sealing mechanism comprising a control member biased to a fixed reference point position and adapted to be moved to a plurality of control positions to predetermine the direction and extent of adjustment of said sealing mechanism, a case gauging member, means for reciprocating the gauging member into momentary engagement with a case on said support from a position beyond the maximum size of case for which the machine is adapted, control member setting means actuated to move proportionately to the movement of the gauging member, means interconnecting said setting means and the control member to cause movement of the control member away from its fixed reference position to com-

mence when the gauging member in moving toward a case to be gauged reaches a position corresponding to the maximum size of case, and means for temporarily retaining the control member in any control position to permit the adjusting movement of the sealing mechanism to be accomplished subsequent to the withdrawal of the gauging member from contact with the case.

38. In a machine of the class described, a case gauging member comprising a reciprocable bar and a plate-like foot member for engaging the case pivoted to the end of said bar, the pivot being arranged to cause the foot to hang in an unbalanced condition with the bottom of the foot normally facing in the direction of an approaching case.

39. In a machine of the class described, the combination of an adjustable sealing mechanism and means for conveying successive cases past said mechanism, of a gauging device for gauging a case dimension, mechanism for actuating the gauging device into engagement with successive cases, mechanism for adjusting the sealing mechanism to an inner position for cases smaller than a predetermined size and to an outer position for cases larger than said size, means cooperating with said gauging device for initiating an adjusting operation of said adjusting mechanism, and means actuated by the movement of the sealing mechanism for terminating the said adjusting movement.

WALLACE D. KIMBALL.
